COMBINED BILLFOLD AND ADVERTISING MESSAGE CARRIER

Norbert Leopoldi, 4180 Marine Drive,
Chicago, Ill. 60613

Filed Sept. 21, 1973, Ser. No. 399,324

Term of patent 14 years

Int. Cl. D3—01

U.S. Cl. D87—3 A

Fig 1

Fig 2

Fig. 3

FIG. 1 is a front and right side perspective view of a combined billfold and advertising message carrier showing my new design in open condition;

FIG. 2 is a sectional view taken along line 2—2 of FIG. 1; and

FIG. 3 is a rear, top and right side perspective view of the combined billfold and message carrier in closed condition.

I claim:

The ornamental design for a combined billfold and advertising message carrier, substantially as shown and described.
